UNITED STATES PATENT OFFICE.

STANLEY BROWN, OF GARDEN CITY, NEW YORK, ASSIGNOR TO THE GRISCOM RUSSELL COMPANY, OF NEW YORK, N. Y., A CORPORATION OF DELAWARE.

EVAPORATOR SYSTEM.

1,405,483.

Specification of Letters Patent. Patented Feb. 7, 1922.

Application filed January 26, 1920. Serial No. 354,000.

To all whom it may concern:

Be it known that I, STANLEY BROWN, a citizen of the United States, residing at Garden City, in the county of Nassau, State 5 of New York, have invented certain new and useful Improvements in Evaporator Systems; and I do hereby declare the following to be a full, clear, and exact description of the invention, such as will enable others 10 skilled in the art to which it appertains to make and use the same.

This invention relates to improvements in evaporator systems, and particularly to a feed water heater whereby the heat usually 15 lost in the "blow-down" of an evaporator plant may be conserved without the addition of costly auxiliary apparatus to the plant.

A further object of the invention is to provide an apparatus for heating the feed water 20 of an evaporator plant in which the concentrated solution constituting the blow-down does not come in contact with any heat transferring surface which would be corroded or scaled by the solution.

25 In the accompanying drawing I have shown in Fig. 1 an evaporator layout containing a feed water heater embodying my invention, and in Fig. 2 a slight modification.

30 In the drawing, which is largely diagrammatic, 1 indicates the first unit of the evaporator plant, here shown as a double effect plant of which the second unit 2 has its heating coils 3 connected to the vapor line 4 of the first unit.

35 The steam coils of the first effect will be connected to a suitable source of live steam (not shown) and the drain from the heating coils of both effects will be led to the hot well 40 of the plant or otherwise disposed of.

In an apparatus of this kind it is frequently desirable to deliver the vapor from the apparatus at a comparatively high temperature, particularly where the apparatus 45 is used to supply the boiler make-up for high pressure steam plants, and as the temperature of the vapor delivered from the last effect determines the temperature of the blow-down, there would be considerable heat 50 lost were the blow-down discharged directly as waste from the evaporator.

The feed for the evaporator plant is delivered to the shell of the first effect through the feed line 5 by the pump 6, and thence 55 to the shell of the second effect through

a feed pipe 7 at the desired water level in the evaporator, a trap 8 being interposed in the line 7 to hold the first effect at the desired operating pressure which must of course be higher than the pressure of the 60 second effect.

It is customary to heat the feed water by means of the exhaust steam from the auxiliary apparatus used in connection with the plant, for instance on shipboard, the 65 steam used for the hoisting engines and similar purposes is used in the evaporator feed heater, and in carrying my invention into effect I use the exhaust steam through the auxiliary steam line 12 for heating the raw 70 water which enters the evaporator feed heater through the pipe 14 and is fed to the evaporator by the pump 6, a separator for removing the oil or other impurities from the steam being preferably inserted in 75 the line.

The blow-down is discharged from the shell of the second effect through a discharge pipe 9 leading from the shell at about the feed level and containing a trap 10 or 80 equivalent device for holding the vapor and allowing the passage of liquid only. In plants of this character, as usually operated, the volume of feed is maintained at such point with relation to the rate of the evaporation in the plant that the overflow through the blow-down is a material portion 85 of the feed, for instance for sea-water operation the blow-down will equal about one-third the volume of the feed, that is, the 90 blow-down is concentrated to three times the salinity of the normal sea water. This amount of water at the high temperature of the vapor discharge represents a considerable quantity of heat and if discharged directly as waste, would materially reduce the 95 efficiency of the plant as a whole. In carrying out the invention of the present application the blow-down discharge pipe 9 leads to a trap 11 and from the chamber or vapor space of the trap a pipe 15 leads to the exhaust steam line 12 which is usually at about atmospheric pressure, thereby relieving the pressure on the blow-down so that the extra heat represented by the temperature above 212 degrees will be converted 100 into latent heat, producing a quantity of steam, the proportion of the steam to the water depending upon the temperature of the blow-down. Thus, if the blow-down is 105

110

at 50 lbs. gauge, the temperature equivalent of which is 297 degrees F. for each pound of water, there will be 297 minus 212, or 85 B.T.U. of heat available for flash.

5 As the latent heat of vaporization at 212 degrees is 966 B.T.U. over 9% of the blow-down will be vaporized and will be available for heating the feed water.

There is no danger of causing impurities 10 in the water by this arrangement, for the reason that while the blow-down is loaded with impurities, the vapor from it will be comparatively clean and contain a lower 15 per cent of impurities than the raw water into which it is delivered in the open heater 13.

In Fig. 2 a different arrangement is shown 20 for accomplishing the same result. Instead of using the trap 11 an S-bend 11' is stalled in the blow-down pipe 9' and above 25 the S-bend an upwardly inclined pipe 15' leads to the exhaust steam line. The S-bend is long enough to cause a back pressure 30 in the blow-down pipe beyond the connection of the pipe 15' for the "flash" to pass 35 through the pipe 15' to the heater, so that only concentrated dirty water at low temperature is thrown away.

A heat exchanger of ordinary construction 30 cannot be economically used for conserving the heat from the blow-down, for it would require an extensive heating surface 35 to absorb any considerable per cent of the heat, and in view of the extreme impurities in the blow-down the heating surface would not be efficient and would require cleaning 40 and repairs to such an extent as to largely offset the heat-saving effected by its use. With the apparatus shown in the drawing, 45 the only addition to the ordinary evaporator plant is the trap or S-bend which is of negligible cost and requires no upkeep whatsoever.

In the accompanying drawings I have 45 shown the evaporator units arranged for series feed, that is, all the raw water is fed to the first effect and all the blow-down is from the last effect which is at the lowest temperature. When the several effects are 50 connected for parallel feed with a blow-down for each effect discharging into a common blow line an even greater quantity of heat will be saved by the invention of this application for the resulting temperature of 55 the blow-down from all the effects will obviously be higher than from the last effect alone.

I claim:

1. In an evaporator system, the combination 60 of a feed heater, an evaporating unit

supplied therefrom comprising means for discharging the concentrated solution, and means for utilizing the vaporous heat of said concentrated solution in said feed heater.

2. In an evaporator system, the combination 65 of a feed heater, an evaporating unit comprising means for discharging the concentrated solution at a temperature above atmospheric boiling point of the solution being evaporated, and means for utilizing in said feed heater the sensible heat contained in 70 said solution in excess of that contained at atmospheric pressure.

3. In an evaporator system, the combination 75 of a feed heater, an evaporating unit comprising means for discharging the concentrated solution at a temperature above atmospheric boiling point of the solution, means for converting the sensible heat contained in 80 said solution in excess of that contained at atmospheric pressure into latent heat of vaporization at atmospheric pressure, and means for utilizing the vapor thus formed in said feed heater.

4. In an evaporator system, the combination 85 of a feed heater having an independent source of vapor for heating the same, an evaporating unit comprising means for discharging the concentrated solution at a temperature above atmospheric boiling point of 90 the solution being evaporated and means for utilizing in said feed heater the sensible heat contained in said discharged solution in excess of that contained at atmospheric pressure. 95

5. In an evaporator system, the combination 100 of a feed heater, an evaporating unit comprising means for discharging the concentrated solution at a temperature higher than the vaporizing temperature corresponding to the pressure in said heater, and means for utilizing in said heater the excess of sensible heat contained in said discharged solution above that contained at the pressure in said heater. 105

6. In an evaporator system, the combination 110 of a feed heater, an evaporating unit comprising means for discharging the concentrated solution at a temperature higher than the vaporizing temperature corresponding to the pressure in said heater, means for converting the excess of sensible heat contained in said discharged solution above that contained at the pressure in said heater into latent heat of vaporization at the 115 pressure of said heater, and means for condensing the vapor thus formed in the feed heater.

In testimony whereof I affix my signature.

STANLEY BROWN.
